ROBOT SCOOP TOY

Sid Noble, Levittown, N.Y., assignor to Ideal Toy Corporation, Hollis, N.Y., a corporation of New York

Application January 22, 1959, Serial No. 54,271

Term of patent 3½ years

(Cl. D34—15)

FIG. 3.

FIG. 4.

Fig. 1 is a front elevational view of a robot scoop toy showing my new design;

Fig. 2 is a top plan view.

Fig. 3 is an elevational view of the left end, as taken in Fig. 1, of the toy.

Fig. 4 is an elevational view of the right end, as taken in Fig. 1 of the toy.

I claim:

The ornamental design for a robot scoop toy, substantially as shown.
